UNITED STATES PATENT OFFICE.

RICHARD KOCKROW, OF NIEDER-LAUSITZ, GERMANY.

PROTECTING-GARMENT FOR AVIATORS.

1,104,808.

Specification of Letters Patent.

Patented July 28, 1914.

Application filed October 10, 1913. Serial No. 794,465.

To all whom it may concern:

Be it known that I, RICHARD KOCKROW, a subject of the Emperor of Germany, residing at Bückgen, Post Grube Ilse, Nieder-Lausitz, Germany, have invented certain Improvements in Protecting-Garments for Aviators, of which the following is a specification.

The present invention relates to a protecting garment for aviators and the like and consists in making such garments out of layers of felt and aluminium which are spaced by spring elements so that, in the case of a fall, the shock will, as far as possible, be neutralized. The innermost layer is composed of felt and is of considerable thickness. This layer is covered by an aluminium layer and both are spaced by means of spring-elements from another aluminium layer. The outer aluminium layer is in its turn covered by a layer of felt or canvas.

Preferably separate garments are made up in this manner for the head, the body and the legs of the aviator, who will then, in case of a fall, at least to a great extent, be protected against the shock.

In the accompanying drawings the invention is illustrated, Figure 1 representing an

edge view of the layers, Fig. 2, a cross-section of the legging, and Fig. 3, a sectional view of the head protector.

The garment is made up of a thick inner layer *a* of felt which is covered by a layer *b* of aluminium. The aluminium layer *b* is spaced by means of springs *c* from another aluminium layer *d* to which, finally, an outer layer *e* of felt or canvas is applied.

The manner in which the elements are combined naturally depends upon the shape of each particular garment. The leggings are preferably constructed as shown in Fig. 2, and the head piece as shown in Fig. 3.

The aluminium layers are made in sections which are connected, for instance like the scales of an armor, so as to allow the necessary movement of the body.

I claim:—

A protecting garment for aviators, such garment being composed of two layers of aluminium covered by felt, and spring elements spacing said layers, substantially as and for the purpose set forth.

RICHARD KOCKROW.
